[57] CLAIM

The ornamental design for a combined toothbrush and holder with integral dental floss dispenser, as shown and described.

DESCRIPTION

FIG. 1 is an exploded top perspective view of a combined toothbrush and holder with integral dental floss dispenser showing my new design, with the right end cap and toothbrush being removed from the holder and the left end cap in open position;

FIG. 2 is a side elevational view of the toothbrush only, shown separately for clarity of illustration, with the opposite side being a mirror image and the bottom being unornamented;

FIG. 3 is a front end elevational view thereof;

FIG. 4 is a rear end elevational view thereof;

FIG. 5 is a side elevational view of FIG. 1 with the toothbrush and dental floss being enclosed in the holder, the opposite side thereof being a mirror image;

FIG. 6 is a left end elevational view thereof; and,

FIG. 7 is a right end elevational view thereof.

FIG. 3

FIG. 4

FIG. 2

FIG. 6

FIG. 7

FIG. 5
